UNITED STATES PATENT OFFICE.

GEORGE A. WELLS, JR., OF NEW YORK, N. Y., ASSIGNOR TO THE COLUMBIA AND ELECTRIC VEHICLE COMPANY, OF JERSEY CITY, NEW JERSEY, AND HARTFORD, CONNECTICUT.

DESIGN FOR A WHEEL-RIM.

SPECIFICATION forming part of Design No. 32,798, dated June 5, 1900.

Application filed November 22, 1899. Serial No. 737,954. Term of patent 14 years.

To all whom it may concern:

Be it known that I, GEORGE A. WELLS, Jr., a citizen of the United States, residing in the borough of Manhattan, city of New York, 5 State of New York, have invented and produced a certain new and original Design for a Wheel-Rim, of which the following is a specification, reference being had to the accompanying drawings, forming a part hereof.

This invention relates to wheel-rims for vehicles, the term "wheel-rim" being here used with a general significance as including the whole of the peripheral portion of a wheel; and the invention consists in the design there- 15 for shown in the accompanying drawings, in which—

Figure 1 represents a wheel-rim which embodies the design as it would appear in cross-section. Figs. 2 and 3 are respectively a 20 view in side elevation and a plan view of such

a rim, the scale being considerably smaller than the scale of Fig. 1 in order to save space.

The body portion *c* of the rim has a convex lower portion and substantially-parallel sides *a a*, slightly outturned, as at *b*, and from the 25 body portion project outwardly two substantially-rectangular portions *d d*, which stand slightly inward from the vertical planes of the sides *a a* of the body portion and are separated by a relatively-narrow space between 30 them, as at *e*.

I claim as my invention—

The design for a wheel-rim, substantially as shown and described.

This specification signed and witnessed this 35 21st day of November, A. D. 1899.

GEORGE A. WELLS, JR.

In presence of—

ANTHONY N. JESBERA,

LOUIS R. MOORE.
